(57) CLAIM

(63) Continuation of application No. 29/083,017, filed on Feb. 2, 1998, now Pat. No. Des. 409,597, which is a continuation of application No. 29/066,478, filed on Feb. 6, 1997, now Pat. No. Des. 390,219.

The ornamental design for a retractable monitor, as shown and described.

(51) LOC (7) Cl. **14-03**

DESCRIPTION

(52) U.S. Cl. **D14/132**

FIG. 1 is an isometric view of a retractable monitor showing my new design from the bottom rear and right side, the monitor being depicted in stowed orientation with monitor environment in dashed lines;

(58) Field of Search D14/371, 374-376,
D14/126, 129, 132; D12/345, 415-418;
D6/300, 513; D8/380; D16/235; D19/60;
D24/158, 160; 108/44, 137; 244/118.5;
248/917-924; 312/7.2; 340/995; 345/905;
348/148, 825, 827, 836-838, 840

FIG. 2 is an isometric view showing the monitor from the top rear and right side and showing the monitor in a display orientation;
